15 Claims. (Cl. 323—43.5)

This invention relates to computers and has particular reference to precision multipliers having electrical and mechanical inputs and an electrical output.

The accuracy requirements of present day analog computers demands extreme precision not available in prior multipliers. Prior devices of this type have included wound resistance voltage dividers or auto-transformers in which the output voltage is proportional to the product of the excitation voltage and the displacement of the movable contact, but in these devices the output varies in finite steps as the contactor moves from turn to turn on the winding. An induction potentiometer, on the other hand, produces a smoothly varying voltage proportional to the product of the excitation voltage and the rotor displacement but is not universally applicable since the linear output is available over little more than 90° of rotor displacement.

In a preferred embodiment, the present invention uses the mechanical input to drive the movable contacts of a pair of selector switches, and to simultaneously drive a pair of induction potentiometer rotor windings. The ratio of speeds is such that for each half revolution of the induction potentiometer rotor the movable contacts travel from one live contact to the selector switch to a similar position on the next adjacent live contact.

Alternate stationary contacts of one selector switch are connected to equally spaced taps on a winding which is energized by the electrical input, and alternate stationary contacts of the other selector switch are connected to taps intermediate of the first taps on the same energized winding. The primary winding of the induction potentiometer is energized by the electrical input. The output of one selector switch is connected in series with one induction potentiometer output while the output of the other selector switch is connected in series with the other induction potentiometer output. Each selector switch provides a voltage which increases in steps as the mechanical input increases while the induction potentiometer acts to interpolate to either side of the step to provide a voltage accurately proportional to the displacement of the input shaft (for constant electrical input) over recurring limits of rotation of about 100° for each half revolution of the potentiometer rotor.

The output of the combination of one selector switch and induction potentiometer winding leads the output of the combination of the other selector switch and induction potentiometer winding by 90° of potentiometer rotor displacement. A make-before-break relay is actuated by the mechanical input to select the output of the proper combination to provide a continuous output which is accurately proportional to the product of the inputs over the complete range of mechanical input.

For a more complete understanding of the invention, reference may be had to the accompanying diagrams in which:

FIG. 1 is a schematic electrical wiring diagram of the invention;

FIG. 2 is a curve of the output of one induction potentiometer winding vs. rotor displacement;

FIG. 3 is a curve of the output of the other induction potentiometer winding vs. rotor displacement;

FIG. 4 is a series of curves showing the outputs of

2

one selector switch, reversing switch and their total output vs. potentiometer rotor displacement;

FIG. 5 is a series of curves showing the outputs of the other selector switch, reversing switch and their total output vs. potentiometer rotor displacement; and

FIG. 6 is a curve showing the output of the present device vs. potentiometer rotor displacement.

Referring now to FIGURE 1, shaft 10 of a computer is driven by means of gearing 11 by the crank 12 which also drives shaft 13. The value X represented by the angular displacement of shaft 10 may be read on dial 14.

The other multiplier Y is represented by an alternating voltage proportional in magnitude to Y which is applied to the input terminals 18'. For the purposes of this description the voltage at terminals 18' will be assumed to be constant and equal to unity so that the output of the multiplier, XY, can be described as being proportional to X. This product XY is obtained at terminals 14' and may be read on the scale of voltmeter V which is connected across terminals 14', for example, or may be used as the input to other computing circuits.

Shaft 13 drives the rotor of an induction potentiometer 17 and displaces the rotor windings 15 and 16 relatively to the stator winding 18. An induction potentiometer is essentially a transformer in which a secondary winding is adapted to be displaced angularly in the field of the primary winding and which is constructed in a manner such that the output voltage of the secondary winding is proportional to the angular displacement of the secondary winding from its position of null voltage (perpendicular to the primary winding) for constant primary excitation. The linear relationship between the displacement and the output voltage is effective for angular values of approximately 50° to either side of the two zero or null positions.

FIGURE 2 which is a curve of the output of winding 15 versus displacement of the shaft 13 for constant excitation at terminals 18' shows that the output voltage of rotor winding 15 is linearly proportional to the angular displacement of shaft 13 from the zero position (i.e. where the magnetic axis of winding 15 is perpendicular to the magnetic axis of winding 18) between approximately -50° and +50°. Also, the output voltage of rotor winding 15 is negatively proportional to the angular displacement of shaft 13 from the 180° position between values of 180° ± 50°, i.e. from 130° to 230°. Between values of 50° and 130° and between 230° and 310° the output voltage of winding 15 does not maintain a linear relationship to the displacement of the shaft 13.

For the purposes of this invention, a second rotor winding 16, perpendicular to the first rotor winding 15, is wound on the rotor of induction potentiometer 17. The output voltage of rotor winding 16 is then proportional to the angular displacement of shaft 13 for 50° on either side of the 90° position of shaft 13 and is negatively proportional to the angular displacement of shaft 13 from its 270° position between the limits of 270° ± 50°. The curve of output voltage of rotor winding 16 versus the displacement of shaft 13 is shown in FIG. 3. In an alternative arrangement, two conventional induction potentiometers having one secondary winding each may be used instead of the single induction potentiometer 17 which has two mutually perpendicular secondary windings 15 and 16.

Shaft 13 also drives the cams 19 and 20 to operate the reversing switches 22 and 23 by means of the cam followers 25 and 27 which are urged against the cam surfaces by the respective springs 26 and 28. Rotor winding 15 is connected to the movable contacts 22a of reversing switch 22. The output of switch 22, taken at terminals 22b is plotted against the rotational displacement of shaft 13 in FIG. 4 and is seen to approximate a saw tooth wave

with flattened peaks. Similarly, rotor winding 15 is connected to the movable contacts 23a of switch 23 so that the output of switch 23, taken at terminals 23b, plotted against the rotational displacement of shaft 13 approximates a saw toothed wave with flattened peaks, as seen in FIG. 5. The output of rotor winding 16 lags the output of rotor winding 15 by 90° of displacement of shaft 13. It will be noted that the cams 19 and 20 cause reversal of the outputs of rotor windings 15 and 16 in the "non-linear" intervals, i.e. near 90° and 270° for winding 15 and near 0° and 180° for winding 16.

Shaft 10 drives the movable contacts 29 and 30 of the multiple selector switches 31 and 32 respectively. Alternate stationary contacts 31a, 31c, 31e of switch 31 are connected respectively to the equally spaced alternate taps 33, 35, 37 of auto transformer winding 40. The tap 33 is the end tap of the winding 40. The alternate stationary contacts 32b, 32d, 32f of switch 32 are connected to the alternate taps 34, 36, 38 on transformer winding 40, said taps being located midway between the taps 33 and 35, 35 and 37, 37 and 39. Contacts 31b, 31d, 31f, 32a, 32c and 32e of the switches 31 and 32 are electrically dead.

The winding 40 is energized by the voltage at terminals 18', and the voltage between any two adjacent taps is designated as 2E. Thus, as shaft 10 drives the movable contact 29 in a direction corresponding to increasing X, the output voltage of switch 31, shown by the dotted curve in FIG. 4, increases by steps of 4E, there being a period of zero voltage between steps as the movable contact 29 rides over a dead stationary contact 31b, 31d, 31f. Similarly, the movable contact 30 of switch 32 is driven about its stationary contacts to produce an output voltage as shown by the dotted curve in FIG. 5, where the voltage increases by steps of 4E after the first step of 2E, and where the action of switch 32 leads the action of switch 31 by 90° of displacement of shaft 13.

Movable contact 29 is connected to one of terminals 22b, while the other terminal 22b is connected to terminal 41 of relay 42, so that the voltage between terminal 41 and the common lead 43, which is connected to end tap 33, is the algebraic sum of the voltage outputs of switches 31 and 22. This voltage may be represented by the solid curve of FIG. 4.

It will be seen that the voltage between terminal 41 and lead 43 varies with respect to the displacement of shaft 13 in the following manner: Between 0 and 50 degrees the voltage is proportional to the shaft displacement; at 50° the movable contact 29 is disconnected from contact 31a to interrupt the circuit and the voltage drops to zero; the voltage remains zero between 50° and 130° while contact 29 rides over contact 31b; at 130° contact 29 cooperates with contact 31c to complete the circuit again, whereby the voltage between terminal 41 and common lead 43 is the sum of the outputs of switches 31 and 22; between 130° and 230° the voltage is proportional to the shaft displacement; at 230° contact 29 is disengaged from contact 31c and the voltage drops to zero until contact 29 reaches contact 31e at 310°; at 310° the circuit is again completed through windings 15 and 40 and the voltage is proportional to shaft displacement up to 360°. This action keeps repeating as the displacement of shaft 13 increases. Although only six contacts have been shown on switch 31 it is apparent that any number of contacts may be used to increase the range of the computer.

In a similar manner the voltage between terminal 44 of relay 42 and common lead 43 is the sum of the voltages from switch 32 and terminals 23b so that the voltage of terminal 44 with respect to lead 43 plotted against displacement of shaft 13 is as shown by the solid line in FIG. 5: Between 0 and 40° the movable contact 30 cooperates with the dead contact 32a so that there is zero voltage at terminal 44; at 40° movable contact 30 engages contact 32b and completes the circuit so that the voltage at terminal 44 is proportional to the displacement of shaft 13 between 40° and 140° displacement; at 140°

movable contact 30 is disconnected from contact 32b so that the voltage at terminal 44 drops to zero and remains at zero up to 220°, i.e. until the contact 30 cooperates with contact 32d; between 220° and 320° the voltage between terminal 44 and lead 43 is proportional to shaft displacement; at 320° the contact 30 leaves contact 32d and the voltage drops to zero. This action keeps repeating for each revolution of shaft 13.

The movable contact 45 of relay 42 is actuated by the cam 46 on shaft 13 for each 90° displacement i.e. at the 135°, 225° and 315° position. Cam 46 operates switch 47 which causes deenergization or energization of relay winding 48 by the power supply 49. The deenergized relay winding 48 allows spring 50 to urge the movable contact 45 downward (in FIG. 1) to cooperate with the spring contact 41' which is connected to terminal 41. An energized relay winding 48 draws the movable contact 45 into cooperation with the spring contact 44' which is connected to terminal 44. Relay 42 is of the make-before-break type, where movable contact 45 momentarily cooperates with both spring contacts 44' and 41' during its operation from one position to the other.

The output of the relay switch 42 taken between contact 45 and the common lead 43 is applied to terminals 14' and it will be seen that this voltage is an uninterrupted, highly accurate voltage proportional to the displacement of shaft 10 or 13 (when the voltage at terminals 18' is unity).

Thus, between 0-45° of shaft 13 displacement relay 30 winding 48 is deenergized, relay contact 45 cooperates with spring 41' and the voltage at terminals 14' is the voltage output of rotor winding 15 represented by the linear output shown in FIG. 4.

At 45° the contact 45 is urged upward by the energized 35 relay winding 48, and during its upward travel cooperates with contact 44' before being disengaged from contact 41'. It is seen that for about five degrees to either side of 45° the voltage at terminals 41 and 44 (with respect to lead 43) are equal so that no damage will result by the momentary short circuit. This make-before-break transfer operation is necessary, on the other hand, to ensure a continuous uninterrupted voltage at terminals 14' for successful operation of servo motors controlled thereby. From 45° to 135° the voltage at terminals 14' increases proportionally as in the linear portion of FIG. 45 5 (between 40° and 140°). At the 135° point, the movable contact 45 is again urged downward as relay winding 48 is deenergized to select the voltage between terminal 41 and common 43 as the output of relay 42.

As the displacement of shaft 13 increases, the relay 42 selects the voltage from either terminal 41 or 44 as prescribed by cam 46 to produce at terminals 14' a voltage proportional to the displacement of shaft 13 or 10.

It will be seen that the cams 19, 20 and 46 do not 55 require extreme precision in manufacture and adjustment since there is a ten degree region in which the transfer from one output to the other may be made, and since the reversal of potentiometer output takes place during periods when the movable contacts 29 and 30 are riding over dead contacts.

We claim:

1. In a device of the character described, a pair of circuits having an output, switch means, and means for selecting either of said pair of circuits and operating said switch means to connect said circuit to said output, a step switch in each circuit, means for driving said step switches simultaneously, potentiometers connected to each of said circuits and means for driving said potentiometers and step switches in predetermined relation.

2. In a device of the character described, a pair of circuits having an output, switch means, and means for selecting either of said pair of circuits and operating said switch means to connect said circuit to said output, a step switch in each circuit, means for driving said step switches simultaneously, potentiometers connected to

each of said circuits and means for driving said potentiometers and step switches in predetermined relation and reversing switches for changing the polarity of the output of said potentiometers.

3. In a device of the character described, a pair of circuits having an output, switch means, and means for selecting either of said pair of circuits and operating said switch means to connect said circuit to said output, a step switch in each circuit, means for driving said step switches simultaneously, potentiometers connected to each of said circuits and means for driving said potentiometers and step switches in predetermined relation and reversing switches for changing the polarity of the output of said potentiometers and means controlled by said potentiometer driving means for actuating said reversing and selector switches.

4. In a device of the character described, a pair of circuits having an output, switch means, and means for selecting either of said pair of circuits and operating said switch means to connect said circuit to said output, a step switch in each circuit, means for driving said step switches simultaneously, an induction potentiometer connected to each of said circuits and means for driving said induction potentiometers and step switches in predetermined relation.

5. In a device of the character described, a pair of circuits having an output, switch means, and means for selecting either of said pair of circuits and operating said switch means to connect said circuit to said output, a step switch in each circuit, means for driving said step switches simultaneously, an induction potentiometer connected to each of said circuits and means for driving said induction potentiometers and step switches in predetermined relation and reversing means for changing the polarity of output of said induction potentiometers.

6. In a device of the character described, a pair of circuits having an output, switch means, and means for selecting either of said pair of circuits and operating said switch means to connect said circuit to said output, a step switch in each circuit, means for driving said step switches simultaneously, a potentiometer connected to each of said circuits and means for driving said potentiometers and step switches in predetermined relation and means controlled by said potentiometer driving means for actuating said reversing and selector switches.

7. In a device of the character described, a pair of circuits having an output, switch means, and means for selecting either of said pair of circuits and operating said switch means to connect said circuit to said output, a step switch in each circuit, means for driving said step switches simultaneously, an induction potentiometer connected to each of said circuits and means for driving said induction potentiometers and step switches in predetermined relation and reversing means for changing the polarity of output of said induction potentiometers and means controlled by said potentiometer driving means for actuating said reversing and selector switches.

8. In a precision multiplier having electrical and mechanical inputs and an electrical output, a pair of circuits, switch means for connecting either of said pair of circuits to said output, a step switch in each circuit, means for driving said step switches simultaneously, potentiometers connected to each circuit and means for driving said potentiometers and step switches in predetermined relation.

9. In a precision multiplier having electrical and mechanical inputs and an electrical output, a pair of circuits, switch means for connecting either of said pair of circuits to said output, a step switch in each circuit, means for driving said step switches simultaneously, potentiometers connected to each circuit and means for driving said potentiometers and step switches in predetermined relation and means for changing the polarity of output of said potentiometers.

10. In a precision multiplier having electrical and me-

chanical inputs and an electrical output, a pair of circuits, switch means for connecting either of said pair of circuits to said output, a step switch in each circuit, means for driving said step switches simultaneously, potentiometers connected to each circuit and means for driving said potentiometers and step switches in predetermined relation and means for changing the polarity of output of said potentiometers and means controlled by said potentiometer driving means for actuating said reversing means and said selector switches.

11. An electrical apparatus, which comprises a series of terminals, one of which is a reference terminal, means for maintaining a reference voltage on the reference terminal and voltages of predetermined values relative to the reference voltage on the respective other terminals along the series, and means for deriving voltages intermediate those on the terminals, said means including a first inductive element connected across two of said terminals along said series, second and third inductive elements positioned in magnetic flux relation with said first inductive element and in quadrature relation with each other, means for continuously varying the magnetic flux relation of said second and third inductive elements with respect to said first inductive element, at least one of said second and third elements producing a linear potential at all times, and means for alternately connecting said second and third inductive elements to successive terminals along the series.

12. An electrical apparatus, which comprises a series of terminals, one of which is a reference terminal, means for maintaining a reference voltage on the reference terminal and voltages of predetermined values relative to the reference voltage on the respective other terminals along the series, and means for deriving voltages intermediate those on the terminals, said means including a first inductive element connected across two of said terminals, second and third inductive elements positioned in magnetic flux relation with said first inductive element and in quadrature relation with each other, means for rotatably varying the magnetic flux relation of said second and third inductive elements with respect to said first inductive element, and means operably connected with said last-named means for connecting said second and third inductive elements to alternate terminals along said series, said means being synchronized to effect said connections during the respective linear ranges of the potentials induced in said second and third inductive elements.

13. An electrical apparatus, which comprises a series of terminals, one of which is a reference terminal, means for maintaining a reference voltage on the reference terminal and voltages of predetermined values relative to the reference voltage on the respective other terminals along the series, and means for deriving voltages intermediate those on the terminals, said means including a first inductive element connected across two of said terminals, second and third inductive elements positioned in magnetic flux relation with said first inductive element and in quadrature relation with each other, means for rotating said second and third inductive elements whereby to vary their magnetic flux linkage with said first inductive element, and switch means responsive to said rotation for alternately connecting said second and third inductive elements to sequential terminals along said series, said switch means being synchronized to effect said connections during the respective linear ranges of the potentials induced in said second and third inductive elements.

14. An electrical apparatus, which comprises a series of terminals, one of which is a reference terminal, means for maintaining a reference voltage on the reference terminal and voltages of predetermined values relative to the reference voltage on the respective other terminals along the series, and means for deriving voltages intermediate those on the terminals, said means including a first inductive element connected across two of said terminals, second and third inductive elements positioned in magnetic flux relation with said first inductive element and in

quadrature relation with each other for inducing overlapping linear potentials in said second and third inductive elements, means for connecting said second and third inductive elements hand-over-hand to successive terminals along said series, and means operably connected with said last-named means for varying the magnitude and phase of the potentials induced in said second and third inductive elements so that the algebraic sum of the linear portion of the induced voltage and the tapped voltage in said second element is always equal to the algebraic sum of the linear portion of the induced voltage and the tapped voltage in said third element.

15. An electrical apparatus which comprises a series of terminals, one of which is a reference terminal, means for maintaining a reference voltage on the reference terminal and voltages of predetermined values relative to the reference voltage on the respective other terminals along the series, and means for deriving voltages intermediate those on the terminals, said means including a

first inductive element connected across two of said terminals, second and third inductive elements serially connected and positioned in magnetic flux relation with said first inductive element and in quadrature relation with each other, means for connecting said second and third inductive elements hand-over-hand to successive terminals along said series, and means operably connected with said last-named means for varying the magnitude and phase of the potentials induced in said second and third inductive elements so that same total potential is developed across each said element from its common serial connection to a reference point throughout the common linear range of the induced potentials.
